UNITED STATES PATENT OFFICE

EDWARD F. TERRY, OF DENVER, COLORADO, ASSIGNOR, BY MESNE ASSIGNMENTS, TO THE GARDNER-DENVER COMPANY, OF QUINCY, ILLINOIS, A CORPORATION OF DELAWARE

LUBRICATOR

Application filed June 19, 1926. Serial No. 117,118.

The present invention relates to lubricators of the type disclosed in my co-pending application for Patent Serial No. 88,866, filed February 17, 1926, which was issued Oct. 23, 5 1928 as Patent No. 1,688,946, wherein a pendulum member is rotatably mounted within the casing, and carries the means for directing lubricant from the reservoir into the air line. In the structure disclosed in that application a two-part casing is employed.

One of the objects of the present invention is to provide a practical structure, in which the lubricant holding casing is formed of one piece, the pendulum member, however, being 15 located therein and operating in the same manner as in the structure above mentioned. This arrangement eliminates one of the joints and consequent chance of leakage, as well as places the pendulum and its mounting so that 20 the possibility of its being tampered with is materially lessened.

The method of forming the lubricator is covered in divisional application Serial No. 167,765 filed Feb. 12, 1927 which issued Jan. 25 31, 1928 as Patent 1,657,597.

In the accompanying drawings:—

Figure 1 is a longitudinal sectional view through the preferred embodiment of the invention,

30 Figure 2 is a cross sectional view on the line 2—2 of Figure 1,

Figure 3 is a detail perspective view of the stem adjusting key that may be employed,

35 Figure 4 is a longitudinal sectional view of the core parts and pendulum member in separated relation,

Figure 5 is a sectional view on the line 5—5 of Figure 4,

40 Figure 6 is a side elevation of the core and pendulum member in assembled relation.

Figure 7 is a sectional view through a mold in completed form for the casting of the casing.

45 Figure 8 is a plan view of the stem-holding spring,

Figure 9 is a view of the spring blank.

In the embodiment disclosed, a single piece casing 8 is provided that is of generally ovoidal form, the ends of the casing being provided with inlet and outlet ports 9, the walls

of which are internally threaded, as shown at 10 for the reception of hose couplings. A lateral opening 11 is also provided, the walls being internally threaded, as illustrated at 12 to receive the threaded end of a closure plug 13. The casing provides an internal lubricant reservoir 14.

A pendulum member is located in the reservoir or chamber 14, and includes a sleeve section 15 having a passageway 16 therethrough, the ends of said passageway being enlarged to provide bearing sockets 17. This sleeve member has depending therefrom a pendulum mass 18, and has an upstanding tubular portion 19 adapted to align with the opening 11. The tubular portion 19 and pendulum mass 18 have a stem chamber 20 that is disposed transversely of the bore 16. In this chamber is rotatably mounted a stem 21 having an annular groove 22 near its upper end. In this groove is located a bowed friction spring 23 that has longitudinally split terminals 24. The spring serves to frictionally hold the stem in place in the chamber, both from longitudinal displacement and in different positions to which it is rotated. Inasmuch as the stem 21 is placed in position after the pendulum is hung on its trunnions within the casing, the spring 23 permits the assembly of the parts.

A lubricant conduit 25 has an inlet end 26 formed in the bottom of the pendulum mass, and extends upwardly where it is in communication with an annular groove 27 formed in the upper end of the stem 21. The inlet end 26 is preferably covered by a screen 28. The stem furthermore has a longitudinal downwardly extending bore or channel 29 in communication with the groove 27, and said channel has transverse outlet ports 30 which open through opposite sides of the stem 21 midway of the bore 16. This stem also has at right angles to the ports 30 fluid inlet ports 31 in communication with a downwardly extending channel 32 that opens through the lower end of the stem into the lower end of the bore or chamber 20. From this lower end a conduit 33 leads upwardly and opens into the upper end of the lubricant reservoir 14.

As will be clear by reference to Figures 1

and 2, the upper end of the stem 21 is adapted to aline with the opening 11, and is thus accessible therethrough. When the plug 13 is removed, means are provided by which the stem 5 can be turned. Thus the said stem is shown as provided in its upper end with spaced sockets 34 adapted to be engaged by the prongs 35 of a turning tool 36, illustrated in Figure 3.

The pendulum member is rotatably supported within the chamber 14 by journal sleeves 37. These sleeves are preferably pressed into the inner ends of the ports 9, inward extensions 38 being formed in the casing as integral parts of the ends thereof, and 10 said sleeves engaging in the journal sockets 17, so that the pendulum member rotates thereon. It will thus be seen that an open-ended passageway for air or other fluid extends directly through the casing, being 15 formed by the terminal ports 9, by the sleeves 37 and the bore 16, and it will also be noted that the conduits 25 and 33 are in communication with said passageway. Consequently if fluid under pressure passes through the 20 passageway and there is lubricant in the reservoir 14, lubricant will rise through the conduit 25, and thence passing downwardly, will escape through the ports 30, where it will be caught by the passing fluid and carried away 25 with it.

Careful investigation of the operation leads to the belief that the action is due to the creation of a partial vacuum on the "down-stream" side of the stem 21, due to the flow of 30 the air around opposite sides of the same. The port 30 opens into this partial vacuum and being in communication with the lower portion of the lubricant reservoir, lubricant will of course flow to and through it to the 35 vacuum and thus find its way into the air stream. The conduit 33 on the other hand appears to act principally as a pressure equalizing vent. For example, it has been found that oil will be delivered freely and effectively, 40 if the conduit 33 is stopped, inasmuch as live pressure finds its way through the passageway 30—29—25. However, if the conduit 33 were 45 not provided, when the air is turned off, the excessive pressure of the compressed air then 50 in the reservoir would react to force all the oil in the reservoir out of the same.

By turning the stem 21, the pressure in the lubricant reservoir can be varied, thus altering the amount of lubricant delivered. It will 55 also be noted that irrespective of how the casing may turn or roll, the pendulum mass will maintain the motive fluid supply and lubricant delivery means always in a vertical position, thus insuring that the inlet end 36 60 of the lubricant conduit will be in the lower-most part of the reservoir or chamber 14, while the fluid delivery conduit 33 will have its outlet end in the upper portion of said chamber.

55 Inasmuch as the casing 8 is of one piece

and the openings 9 and 11 are of less size than the pendulum member, it has been a problem as to the placing of the pendulum member within the casing and mounting it. This problem has been solved in the following manner.

The casing being of metal, preferably cast, a core for the interior has been formed of two sections, as illustrated in Figures 4 to 7, the sections being respectively designated 39 and 40. The sections when placed together, as illustrated in Fig. 6, produce the complete core, constituting a body or chamber-forming portion 41, stems 42 which produce the end ports 9 in the casing, with anchoring terminals 43, and an upstanding stem 44 that forms the opening 11. The body portion 41 is of sufficient size to receive a completed pendulum member. Consequently the sections of said body member are formed with sockets 45 and 46 in which the pendulum member is received, said member being preferably, though not necessarily located at right angles to its final position, as will be clear by reference to the aforesaid figures. The pendulum member therefore having been introduced and the core sections fitted together, the joint between them is sealed, and the cavity 47 for the casing having been formed in a mold in the usual manner and as indicated in Figure 7, the core is introduced, the mold sections placed together and the casting made.

The mold is then broken, the casting removed and the core is broken and removed, leaving the pendulum member within the casing. After the casing has been dressed and fitted, the journal sleeves 37 are then pressed into the extensions 38, with their inner ends engaged in the journal sockets 17 of the pendulum member, the fitting being of course such that the pendulum will rotate thereon. This completes the mounting for the structure, as shown in Figures 1 and 2.

From the foregoing, it is thought that the construction, operation and many advantages of the herein described invention will be apparent to those skilled in the art without further description, and it will be understood that various changes in the size, shape, proportion and minor details of construction and method of operation may be resorted to without departing from the spirit or sacrificing any of the advantages of the invention.

What I claim is:—

1. In a lubricator, the combination with a single piece casing body enclosing a lubricant reservoir, of a pendulum member located within the reservoir, means carried by the casing on which the pendulum is mounted, a passageway through the casing and pendulum member for the flow of fluid and of less cross sectional area than the reservoir and pendulum, and means carried by the pendu-

lum member for directing lubricant from the reservoir into the passageway.

2. In a lubricator, the combination with a single piece casing body enclosing a lubricant reservoir and having end ports of less cross

5 sectional area than the reservoir for the inflow and outflow of fluid, of a pendulum member of greater cross sectional area than the ports, said member being located within the 10 reservoir and having a passageway therethrough for the passage of fluid entering and leaving the ports, journal sleeves fitted in the ports and engaged with the pendulum member, and means carried by the pendulum 15 member for directing lubricant from the reservoir into the passageway.

3. In a lubricator, the combination with a casing body enclosing a lubricant reservoir and having end ports for the inflow and outflow of fluid, of a pendulum member located 20 within the reservoir and having an open ended passageway therethrough in line with the casing ports, journal sleeves fitted into the ports through the outer ends thereof and 25 into the ends of the passageway, and means carried by the pendulum member for directing lubricant from the reservoir into the passageway.

4. In a lubricator, the combination with a 30 casing forming a lubricant reservoir and having an opening in one side, of a pendulum member rotatably mounted in the casing and having a fluid passageway therethrough and a chamber with an open end that is adapted 35 to align with the casing opening, a lubricant controlling stem that is mounted in the chamber and is insertible and removable through the casing opening, and means for holding the stem in place, said means being 40 insertible with the stem through the casing opening and frictionally holding the stem in place while permitting its removal.

5. In a lubricator, the combination with a 45 casing forming a lubricant reservoir and having an opening in one side, of a pendulum member rotatably mounted in the casing and having a fluid passageway therethrough and a chamber with an open end that is adapted to align with the casing opening, a 50 lubricant controlling stem that is rotatably mounted in the chamber and is insertible and removable through the casing opening, and a spring carried by the stem and frictionally engaging the wall of the chamber for holding the stem in place and permitting its 55 removal, said spring being insertible with the stem through the casing opening.

6. In a lubricator, the combination with a 60 single piece casing enclosing a lubricant reservoir and having end ports and an opening in one side, of a pendulum in the casing of greater size than the opening, said pendulum having a passageway therethrough, and means for directing lubricant from the 65 reservoir into the passageway, and sleeves

engaged in the ports and the ends of the passageway and constituting journal members that permit the pendulum to rotate in the casing.

7. A lubricator comprising side and end 70 walls, forming a lubricant reservoir, a pendulum member within the casing, sleeves tightly fitted against movement in the end walls and having journal engagements with the pendulum, said sleeves constituting 75 means for journaling the pendulum to permit it to swing and also forming with the pendulum a passageway for fluid through the casing, and means carried by the pendulum 80 for directing lubricant from the reservoir into the passageway.

8. A lubricator comprising side and end 85 walls that are integral to form a single piece casing that encloses a lubricant reservoir, said end walls having coupling elements provided with openings, a pendulum in the reservoir of greater size than the openings and having a passageway through it, sleeves engaged in the openings and passageway and constituting with the passageway means of 90 communication between the coupling elements, and means carried by the pendulum for directing lubricant from the reservoir into the passageway.

9. A lubricator comprising side and end 95 walls that are integral to form a single piece casing that encloses a lubricant reservoir, said end walls having coupling elements provided with openings, a pendulum in the reservoir of greater size than the openings but narrower than the space between the end 100 walls, said pendulum having a passageway through it, sleeves engaged in the casing openings, bridging the spaces between the end walls and the pendulum and engaged in the passageway of the pendulum, said sleeves and passageway constituting with the passageway means of communication between the coupling elements, and means carried by the pendulum 105 for directing lubricant from the reservoir into the passageway.

In testimony whereof, I affix my signature.

EDWARD F. TERRY.
